FLUSH TANK VALVE

Anthony Ross Rosano, Toronto, Ontario, Canada

Application April 20, 1942, Serial No. 439,624
In Canada April 8, 1941

4 Claims. (Cl. 4—57)

This invention relates to improvements in a flush tank such as is commonly used for domestic purposes.

The main object of this invention is to provide a tank with improved emptying facilities into the bowl with which it is associated. Heretofore in tanks of this description manually operable lever means for the flush valve were provided usually in the upper regions of the tank. The ball or siphon valve, as the same is known, usually depended from the end of a rod which co-operated through a series of arms, levers and links with the handle member.

By means of my construction I have eliminated these features. I affix the ball valve on the end of a rod extending downwardly therefrom and I operate the same by engaging the free end thereof by means of a rock arm. Where previously frequently the handle means for operating this valve were at the top of the tank for the obvious purpose of avoiding the danger of leaks by entering the tank below the water line, by my construction no moving parts other than the ball valve itself extend into the tank. All other parts are disposed in the adjacent portion of the drain pipe connecting the tank with the bowl.

I realize that tanks have been previously constructed with valve means operable below the tank, and I do not intend to claim such a feature generally.

The objects of my invention may be concisely stated as embracing, firstly: to provide manually operable lever means for opening the valve positioned below the lever of the tank; secondly: to provide such means which are simple in structure, economical to manufacture, durable in character, and consisting of relatively few parts; thirdly: the provision of a valve of the character described which is easy to assemble and to disassemble; and fourthly: to provide valve means which may readily be incorporated into a fixture of the old style without disturbing the existing tank.

Further and other objects will become apparent from a further reading of this specification taken together with the drawing forming part thereof.

Referring to the drawing wherein like characters represent like parts throughout the various views.

Figure 1 is a sectional view in elevation of a valve constructed according to this invention.

Figure 2 is a top plan view of the tank showing the arrangement of the parts.

Figure 3 is a plan view of the mechanism with the valve member removed.

The tank 13 is connected to the drain pipe 10 leading to the usual bowl mechanism not shown in the drawing. The siphon valve 1, its associated valve seat 2, and the overflow 3 are of orthodox construction. I provide a rod 4 slideable within a stationary tube or bearing 5 positioned at the mouth of the drain pipe 10, on a crossbar 6. A T-extension 11 is provided in the vertical portion of the drain pipe. The mouth of the T extension is sealed by a relatively heavy flexible disc 8, a lever 9 is fulcrumed through the disc 8. The end of the inwardly extending portion 15 of the lever 9 is adapted to engage the free end of the rod 4 in such manner that downward manipulation of the handle means 18 affixed at the end of the outwardly protruding portion of the lever arm 9 raises the rod and brings the siphon 20 valve to open position.

To avoid disengagement between the rod and its bearing the free end of the former is enlarged. The assembling of the parts is naturally accomplished before the valve and the rod are secured together which may be by any known method. In the drawing the two are shown threaded together in a well understood manner. The free end of the rod is preferably rounded to minimize friction when actuated by the lever 30 during operation.

Since the rock lever is fulcrumed in the flexible disc 8 it must be guarded against both rotation and lateral displacement either of which may tend to disengage the foot of the rod and the contact face of the rock lever. There are many ways which this can be accomplished; in Figure 3 a very simple device for this purpose is shown. The nut 17 utilized to retain the disc in place is provided with an externally extending flange or body portion. This is drilled preferably on a vertical plane to admit a pin 23. The rock lever 9 is provided with a longitudinal slot 22 through which the pin beforementioned extends. Thus, both rotation and lateral displacement of the lever is eliminated. For practical reasons it may be found preferable to dispose the slot 22 in such manner that the pin 23 will depend from the tank bottom and extend therethrough, or the objective may be achieved by linking together loosely the free end of the rod and the adjacent end of the lever in any well known manner.

In constructing the extension of the drain pipe a flange 19 shown in Figure 1 is provided against 55 which the flexible disc 8 abuts, it is held in place

by a nut 17 threaded over the mouth of the T and compressing peripheral portions of the disc to provide a water-tight seal. It will be understood of course that this flange is not essential and that the disc can be laid against the mouth of the T and clamped into position as previously described by a suitable nut. In the drawing the securing together of the rock lever and the disc is shown accomplished by means of a threaded portion on the lever and two opposing nuts with sections of the flexible disc clamped between them. This type of construction is of course in its simplest form and is capable of many modifications none of which, however, would depart from the spirit of this invention.

The conversion of an existing fixture to operate according to my invention is very simple. The manner of installing the cross bar 6 carrying the tubular bearing and rod is obvious and need not be explained. A slot is opened in the side wall of the drain pipe 10 of a sufficient width to admit the rock lever 1 with relatively little side play and of a sufficient length to permit the necessary vertical movement of the lever when it is actuated. The T-like extension 11 is secured in place by brazing or soldering or by any other method so as to completely circumscribe the slot. With this construction no additional device for guarding against lateral or rotational displacement of the rock lever is necessary such as in Figure 3 where a slot and pin arrangement represented by the characters 22 and 23 respectively are shown. If the intruding portion of the rock lever be rectangular in section, and if the slot be made to provide a relatively snug fit in width there will be no opportunity for the lever to either rotate or be displaced laterally.

It will be readily seen that the construction of the emptying mechanism disclosed by my invention is infinitely simpler than the mechanism heretofore employed in tanks of this character, and that the number of moving parts have been reduced to an absolute minimum, namely two elements, the rock lever and the engaging rod carrying the ball valve. By utilizing my improved construction there is the elimination of the clanging noises which previously accompanied the flushing operation. And furthermore, by disposing the parts as here indicated the operating handle is removed to a point below the tank itself and thereby generally enhances the appearance of the fixture.

While I have described a certain construction form which embodies the principles of my invention, it will be obvious that many desired changes in arrangement may be made without departing from the spirit of this invention as defined in the appended claims.

Claim:

1. A discharge mechanism for a flush tank comprising the usual drain pipe, valve seat and ball valve fitted with a depending stem, a centrally disposed tubular bearing secured to a stationary arm within the said pipe below the seat adapted to support the said valve stem for vertical reciprocation therewith, a vertical slot in the pipe wall substantially opposite the free end of the valve stem, a perforated flexible member overlying the same and sealing the margins thereof, a rock lever fulcrumed through the said per-

foration the intruding end whereof engages the free terminus of the valve stem for the purpose of raising the valve to open position and the outwardly extending end provides handle means for its manual manipulation, means for retaining the said lever against rotatable and lateral displacement.

2. A discharge mechanism for a flush tank comprising the usual drain pipe, valve seat and ball valve fitted with a depending stem, a centrally disposed tubular bearing secured to a stationary arm within the said pipe below the seat adapted to support the said valve stem for vertical reciprocation therewith, a vertical slot in the pipe wall substantially opposite the free end of the valve stem, a perforated flexible member overlying the same and sealing the margins thereof, a rock lever sealed through the perforation and fulcrumed thereat the intruding portion whereof extends through the said slot and has sectionally rectangular portions adjacent thereto with a minimum of side clearance with the vertical slot edges and the end whereof engages the said stem for raising the valve to open position and the outwardly extending end provides handle means for its manual manipulation.

3. A discharge mechanism for a flush tank comprising the usual drain pipe, valve seat and ball valve fitted with a depending stem, a centrally disposed tubular bearing secured to a stationary arm within the said pipe below the seat adapted to support the said valve stem for vertical reciprocation therewith, a lateral T-like extension in the wall of the drain pipe circumscribing a vertical slot therethrough substantially opposite the free end of the valve stem, a perforated flexible member clamped over the mouth of the extension, a rock lever sealed through the perforation and fulcrumed thereat the intruding portion whereof extends through the said slot and has sectionally rectangular portions adjacent thereto with a minimum of side clearance with the vertical slot edges and the end whereof engages the said stem for raising the valve to open position and the outwardly extending end provides handle means for its manual manipulation.

4. A discharge mechanism for a flush tank comprising the usual drain pipe, valve seat and ball valve fitted with a depending stem, a centrally disposed tubular bearing secured to a stationary arm within the said pipe below the seat adapted to support the said valve stem for vertical reciprocation therewith, a lateral T-like extension in the wall of the drain pipe circumscribing an opening therewith substantially opposite the free end of the valve stem, a perforated flexible member clamped over the mouth of the extension sealing the margins thereof, a rock lever sealed through the perforation and fulcrumed thereat the intruding end whereof engages the free terminus of the valve stem for the purpose of raising the valve to open position and the outwardly extending end provides handle means for its manual manipulation, means for retaining the said lever against rotatable and lateral displacement comprising a stationary pin vertically disposed extending through a longitudinal slot in the body of the lever.

ANTHONY ROSS ROSANO.
